UNITED STATES PATENT OFFICE

PARK E. WELTON, OF CUYAHOGA FALLS, OHIO

FUEL BRIQUETTE

Application filed November 4, 1926. Serial No. 146,272.

This invention is concerned with fuel briquettes and has for its general object, the provision of a briquette structure which, when subjected to heat, will tend to increase its exposed area to kindling action of fire.

A further object of my invention is the provision of a particular briquette structure directed to the facilitating of rapid kindling and conducive to the maintaining of an efficient combustion when placed in the fire box and of a shape which will tend to preserve the briquette structure during the shoveling or handling and shipping of the briquette.

Other objects of my invention will herein after be set forth in the following description which refers to the accompanying drawings, illustrating a preferred form thereof. The essential characteristics are summarized in the claims.

20 In the drawings, Fig. 1 is a perspective view of a briquette embodying features of my invention; Fig. 2 is a fragmentary detail thereof and Fig. 3 is a cross sectional view taken substantially along the line 3—3 of Fig. 1.

It has been the practice heretofore to form fuel briquettes by utilizing waste by-products of many industries, such as saw dust, wood chips, coke, breeze etc. but the modern development of the art has been directed to the reclamation of coal culms, which when properly treated with a combustible binder, can be economically formed into commercially practical fuel briquettes. My present invention is concerned primarily with the physical structure of briquettes formed out of coal culm and constitutes an improvement on the form of briquette. I have disclosed in my Patent 1,572,629, issued February 9, 1926 on a 40 "method of making fuel briquettes". The material comprising the briquette however, may be any economically suitable material which can be treated in a practical manner with a binder to cause the material to hold its shape when extruded by a suitable apparatus.

The shape of the briquette as well as its structural characteristics has a direct bearing upon the efficiency with which the briquette can be handled and eventually burned.

For example, a cylindrically formed briquette of a granular structure has advantages over other forms of briquettes in that when the briquette is being handled, usually with a shovel, the shoveling action does not 55 produce undue crumbling of the briquette even though it may be granular and when the cylindrical briquette is placed in the firebox, there is no tendency to pack and interfere with proper draft for only line or point 60 contacts are present between the briquettes when in the firebox; and further if the cylindrical form is also hollow, that is, of a tubular shape, additional gas escaping surfaces 65 are provided whereby volatile matter not only escapes from the briquette around the cylindrical surface thereof, but escapes into the interior and burns at the ends of the briquette and if these ends are jagged or irregular and of an open porous structure relative 70 to the exterior surface of the briquette a more ready kindling of the briquette takes place at the ends thereof. To increase the area of the briquette which is exposed to flames, I 75 form the briquette in such manner that there will be present in its wall structure definite planes of cleavage whereby when the briquette is subjected to the heat, the briquette wall will have a tendency to part along these cleavage lines and thus provide an increased 80 area exposed to flame and heat and this affords a more ready escape of the volatile matter from the body of the briquette. This briquette structure may be obtained by forming 85 a cylindrically shaped briquette as shown in Fig. 1, which will have a cleavage plane, preferably spiral in form, as indicated at 5 and 6 which is defined by juxtaposed convolutions of the briquetted material, which when 90 being compressed preferably by an extruding process, will cause convolutions of the material varying in density in the briquette body to produce these planes of cleavage. These planes of cleavage do not interfere 95 with the bonding of one convolution of the briquetted material to an adjacent convolution whereby when the briquette is manufactured and up to the time it reaches the fire box, it is tubular in form with a uniform outer cylindrical wall surface. The bri-

100

quette when broken will have the jagged ends as represented in Figs. 1 and 2 if formed of the materials set forth in the following paragraph and these broken jagged ends facilitate the kindling of the briquette.

Obviously the article herein shown and described may be formed by various methods. An example of an apparatus by which the article may be formed is found in my prior Patent, No. 1,652,189, issued December 13th, 1927. In this patent there is shown a tapered extruding worm operating within the confines of a cylindrical die. The threaded portions of the worm substantially fill the die, and therefore, assuming that the material urged forwardly into the die by the worm is prevented from revolving, the material fed past the end of the worm will be in the form of a strand. Now, by reason of the fact that the material is left packed and fairly smooth where the extruding faces of the threads engage the material, a distinct seam will be formed between adjacent convolutions of the spiral strand. Subsequent confinement of the tubular body so formed is just enough to bring one convolution of the strand tightly against another, but there is not enough pressure brought into play to cause the material of the adjacent strands to commingle, the pressure being simply enough to cause the strands to stick together. Prior to the Welton machine above referred to, extruding worms and cylindrical dies of the same general character had been used. One difference between my patented structure and prior apparatus, and which I believe accounts for the peculiar result herein set forth and claimed, is that at the end of the worm the threads are reduced in pitch, that is to say, at the very end of the worm the threads are closer together, resulting in that a final packing is given to each individual strand, and in this final packing the thread engaging surfaces of the strands are hardened to such an extent that subsequent movement through the die does not cause more than simple adhesion between adjacent strands.

It is to be understood that the article herein disclosed may be made by any method wherein the surfaces adjacent each other are smoothed, hardened, or otherwise treated in such manner that there is a distinct seam at these surfaces in the finished article.

The preferred material for forming my briquette may comprise anthracite culm properly graded and screened whereby when mixed with a suitable powdered binder, a briquette having a granular porous structure may be produced. A sulphite binder such as a cellulosic sulphite by-product incident to the manufacture of sulphite paper pulp may be mixed with the dried culm in pulverized form. A water-proofing material in the form of shredded petroleum, residue

wax or asphaltum may be incorporated in the mix. The batch when properly moistened with water can then be formed into briquettes by the application of pressure thereto.

In Fig. 3, I show in cross section, the wall structure of the tubular briquette shown in Fig. 1 and if desired an interior spirally curved effect, as shown at 7, may be produced, which groove is coincident with the planes of the spiral convolutions of briquetted material which form the cylinder shown in Fig. 1. This groove has the tendency to more clearly define the cleavage planes between the convolutions of compressed granular material.

I am aware that efforts have been made in the past to produce a laminated fuel, comprising laminated layers of treated culm which will tend to separate in the fire and thus expose a greater combustion area, but I believe I am the first to disclose a tubularly formed briquette structure which has all of the advantages of the more expensive laminated fuel referred to but which is obtained more economically by forming definite planes of cleavage in the walls of the tube which planes do not extend longitudinally of the tubular briquette structure but transversely. It is to be understood that materials other than those herein set forth may comprise the body of the briquette and which may be treated to produce the briquette structure I claim herein.

I claim:

1. A fuel briquette, tubular in shape and having a spiral cleavage extending throughout its wall.
  2. A cylindrical briquette comprising spirally formed convolutions of briquetted material.
  3. A tubular laminated briquette, built up of laminations of briquetted material, the laminated surfaces extending transversely of the briquette structure.
  4. A fuel briquette, granular in structure and tubular in shape and having a spiral cleavage extending throughout the granular structure thereof.
  5. A cylindrical briquette, comprising spirally formed convolutions of bonded material granular in structure and tubular in form.
- In testimony whereof, I hereunto affix my signature.
- PARK E. WELTON.
